VALVE TOOL

Harry W. Kulp and Martin C. Dellinger, Lancaster, Pa., assignors to K-D Manufacturing Company, Lancaster, Pa., a corporation of Pennsylvania

Application June 15, 1934, Serial No. 730,833

9 Claims. (Cl. 29—86.3)

This invention relates to pry-bar type valve spring lifters for use in the removal and replacement of valve units and for the compression of the valve springs incident to the operation of 5 grinding the valves of automobile internal combustion engines, and is primarily intended for use with the V-type of multiple cylinder engines.

At least one currently popular make of automobile has the valve guide bores in its engine 10 block of such size that the divided valve-stem bushing or bearing together with the valve-spring and spring retaining washer or plate may be inserted as a unit endwise from the top of the block and may be similarly withdrawn, a retaining 15 plate or keeper slidably engaging in a groove in the bushing and engaging the engine block under the thrust of the valve spring serving to lock the unit in place in the engine block in normal assembled relation. In order to grind the valve 20 in this make of automobile engine it is necessary to remove the retaining plate or keeper, force the unit as a whole upward to free it from adhesion with the engine block and thereafter remove it from the engine block, compress the spring so as 25 to remove the spring-retaining washer, after which the spring, guide bushing and retaining washer are removed from the valve stem and the valve is replaced in the engine block in association with a temporary guide bushing, according to 30 usual known practice, and ground. To replace the valve units the units are first reassembled, then inserted in the engine block, the valve spring compressed downwardly and finally the unit retaining or keeper plates are inserted.

The present invention has been developed with the above considerations in mind and has primarily in view the provision of a single tool capable of efficiently performing the several lifting and depressing operations as well as the compressing operations required; to provide a tool 40 which may be used as a pry-bar type tool for the several lifting and depressing operations and which may have its parts shifted in position with relation to each other to act as a plier-type or 45 tweezer type tool for the compressing operations and in which the members will be spring-pressed away from each other and may be forced toward each other simply by the grip of one hand, or by being inserted between the jaws of a vise, according as may be most convenient or preferred, 50 to compress a valve spring of a removed valve unit; and to provide a very simple sturdy quickly separable pivotal connection for associating the two sections of the tool for use as a spring-compressor.

In the accompanying drawings, in which we have shown merely the present preferred embodiment of our invention simply by way of illustration of the practice thereof, and with no thought or intention of being limited to the specific form shown:

Figure 1 represents a perspective view of a tool embodying our invention;

Figure 2, a side elevation thereof as applied in use to depress a valve spring preparatory to removing the valve unit retaining or locking plate;

Figure 3, a perspective separated or "exploded" view of the adjacent portions of the interlocking ends of the sections as used as a pry-bar type of tool;

Figure 4, a sectional view on the line 4—4 of Figure 5, looking in the direction of the arrows;

Figure 5, a sectional view on line 5—5 of Figure 4, looking in the direction of the arrows;

Figure 6, a view similar to Fig. 2 showing the 20 tool as applied in use to lift or "kick" a valve unit out of the engine block after the removal of its retaining or locking plate;

Figure 7, a side elevation of the tool, after its sections have been shifted into plier or tweezer 25 relationship, as used to compress the spring of a valve unit, the tool being illustrated as held between the jaws of a vise indicated by dotted or broken lines;

Figure 8 a fragmentary view, partly in section 30 and partly in side elevation of the hinge connection between the sections and of adjacent parts of said sections when associated for spring compressing use;

Figure 9, a sectional view on the line 9—9 of 35 Figure 8, looking in the direction of the arrows; and

Figure 10, a sectional view on the line 10—10 of Figure 8, looking in the direction of the arrows.

Referring now in detail to the drawings, the tool, which is an improvement on our invention described in our pending application Ser. No. 662,332, filed March 23, 1933, for Valve spring lifters, comprises two channel bar form sheet metal sections 1 and 2 having bifurcated jaw portions or ends 3 and 4 respectively at their distant ends and having their adjacent ends formed for interlocking overlapping relationship to form a rigid two-part pry-bar tool. To this end the end of section 1 adjacent section 2 has its sides inwardly offset to be received between the sides of the adjacent end portion of section 2. The end portions of said offset side portions of section 1 are formed with longitudinally extending 50 55

slots 7 to receive the cross-pin 8 extending through section 2 and similarly the corresponding end portions of the sides of section 2 are provided with similar longitudinal slots 6 to slidably receive the 5 protruding end portions of the pin 5 extending through the sides of the offset end portion of section 1, a locking member 10 serving to lock the sections together in pry-bar relationship. Said locking member 10 is permanently connected to 10 the section 2 by being pivotally mounted on the pin 8 and is held in normal locking position by a tension spring 18 and has open slots 6' intersecting the slots 6, all as more fully described in our said above referred to application Ser. No. 15 662,332.

The locking member 10 is preferably formed of two pieces of sheet metal having their upper portions spread to snugly receive between them the intervening portion of the section 2 and 20 having the immediately next adjacent lower portion and the end portions preferably parallel and in contact with each other and secured together permanently in any usual known and convenient manner as by spot welding, the medial lower portions 25 of said plates being spread apart preferably from their lower edges into substantially parallel relationship to form a spacing and bearing portion 12 of said locking member 10, said portion 12 being of such thickness as to make 30 a snug sliding and turning fit between the opposed inner faces of the inwardly offset end portions of the section 1 and about the flattened cross-bar or hinge pintle 15 extending between and through the sides of said inwardly offset end portion 35 of said member 1.

Said spacing and bearing portion 12 is formed with a slot 14 of a width corresponding to the thickness of the said cross-bar or pintle 15 or very slightly in excess thereof to slidably receive 40 the same and extends from the lower edge of said portion 12 upward to a rounded enlargement 16 having a diameter corresponding to, or slightly in excess of, the width of said cross-bar or pintle. A leaf spring 21 secured against the 45 inner face of the web or top of section 1 by any suitable means as by a rivet 23 bears with its free end against the edge of this spacing or bearing portion 12 or other part of the member 10 to force the two sections 1 and 2 apart about the 50 axis of the cross-bar or pintle 15 when the two sections 1 and 2 are associated in plier or tweezer relationship for use in compressing springs, all as clearly illustrated in Figures 8 and 9.

A lug plate or projection 19 to serve as a fulcrum 55 point to bear against the lower faces G of the engine flanges when using the tool to depress the springs A downward to remove the unit retaining or locking plates b is provided on the section 1 adjacent its jaw 3 and may be formed 60 or provided in any convenient known manner, though preferably the same is formed of a piece of sheet metal secured to the web of section 1 in any convenient manner as by spot welding and having its edge portions bent upwards parallel to 65 each other and at right angles to said web and formed intermediate their length with upstanding rounded edge portions to serve as a rounded fulcrum bearing surface.

In operation, the two sections 1 and 2 are 70 associated together as illustrated in Figures 1 to 6 for use as a pry-bar. The jaw 3 is then inserted between the helices of a spring A adjacent the upper end thereof and with the lug plate 19 presented toward the adjacent face G of the adjacent 75 engine flange, the tool then is tilted until lug

plate 19 engages said faces G, when pressure is exerted in the direction of the arrow, as indicated in Figure 2, to pull the valve unit locking plate b down slightly below face G to relieve said plate b from the influence of the valve spring A so that 5 said plate b may be pulled in a direction parallel to the face G from its annular receiving groove b' in its divided valve stem guide or bearing bushing B. After said locking plate b has been thus removed, the jaw 3 is pulled free from the spring 10 A, the jaw 4 then being inserted between the helices of the spring A, the tool being tilted to bear against the point or corner H of the distant engine flange and pressure being applied to the tool in the direction of the arrow as illustrated 15 in Figure 6 to break the grip of the gummy oil, carbon and other adhesions and to force or kick the valve unit upward through the head of the engine block. Thereafter the jaw 4 is pulled free of the spring A, the valve head D is then 20 gripped by hand and the valve unit is lifted by hand from the engine block. With this accomplished, the sections 1 and 2 are separated and re-associated, this time for use as a spring compressor, the cross-bar or pintle 15 being introduced into the slot 14 and being moved endwise thereof until it enters the enlarged rounded portion 16, at which time the sections 1 and 2 are moved toward each other, so locking the said sections together until they are again moved to substantially right angles to allow the cross-bar or pintle 15 to be withdrawn lengthwise of the slot 14. As the said sections 1 and 2 are moved from a right angle relationship toward each other about the axis of the cross-bar or pintle the end 30 of the spring 21 engages the edge of the portion 12 or other edge portion of member 10 and tends to force said members 1 and 2 away from each other. As thus associated in plier or tweezer relationship, the jaw 4 is applied against the upper 40 end of the split bushing B and the jaw 3 against the lower end of spring A and the two sections 1 and 2 are then moved toward each other about the axis of pintle 15, thus compressing spring A and allowing keeper E, normally resting on and 45 held by enlarged or mush-room form lower end F of the valve stem C to be removed in a direction transverse of the stem C, when the valve unit is removed from the jaws 3 and 4, the spring A removed endwise from the valve stem C, the sections of the bushing B being then separated and removed. After the valve has been ground the bushing B is replaced on the stem, the spring A slipped over the lower end of the stem, the jaws 50 3 and 4 are again applied to the lower end of the spring A and the top of bushing B respectively and moved toward each other, compressing the spring A, when the retainer E is replaced on the stem C and the unit again removed from the jaws 3 and 4, the reassembly of the valve unit being 60 thus completed. Thereafter said unit is reinserted in its valve bore in the engine block, the sections 1 and 2 being separated and reassociated as a pry-bar, the jaw 3 is again inserted between the helices of the spring A with the lug plate 19 65 presented toward the face G of the adjacent engine flange, pressure being applied to the tool in the direction of the arrow as illustrated in Figure 2 to again depress the spring A, this time to allow the unit locking or retaining plate b to be 70 reinserted in its annular groove b' in the bushing B to again lock the valve unit in operative relationship in the engine block, after which the jaw 3 is pulled from between the helices of that spring A and the job of removal, valve grinding, and 75

replacement is finished as to that particular valve unit.

Having thus described our invention, what we claim as new and desire to secure by Letters 5 Patent is:

1. A valve tool comprising a pair of sheet metal channel form lever sections having their outer end portions formed with bifurcated jaws for use in lifting, depressing or compressing a valve 10 spring and having their inner end portions formed to adapt them to interlock to form a rigid pry-bar type valve spring lifter and depressor, in combination with a flattened pivot pin extending between and rigidly mounted in the sides of and carried by the inner end portion of one of said sections, a leaf spring mounted on the inner face portion of the web of said lever and having its free end adjacent said pin spaced from said web, a manipulating grip piece constituting a spring actuated latch pivotally connected to the inner end portion of the other lever section and adapted to releasably engage the inner end portion of the pin carrying section to lock said sections in interlocked pry-bar 15 relationship, said grip piece being formed with an open end key-hole slot to slidably and rotatably receive said pivot pin to detachably connect said sections together in spring compressing plier relationship, said spring in such relationship engaging with its free end the opposed edge portion of said grip piece and exerting force tending to move said sections away from each other about the axis of said pivot, and said grip in all directions about said key-hole slot being of such thickness as to make a snug rotary sliding fit between the opposing inner faces of the sides of said pivot pin carrying section to maintain the sections in proper alignment in such spring compressing plier relationship. 20
2. A valve tool comprising a pair of channel form sheet metal lever sections having their outer end portions formed with bifurcated jaws for use in lifting, depressing or compressing a valve spring and having their inner end portions formed to adapt them to interlock to form a rigid pry-bar type valve spring lifter and depressor, one of said sections being formed adjacent its jaw with a projection to engage an opposed face of the engine block to constitute a fulcrum point 25 in depressing a valve spring, in combination with a flattened pivot pin extending between and rigidly mounted in the sides of and carried by the inner end portion of one of said sections, a leaf spring mounted on the inner face of the web of said section and having its free end adjacent said pin spaced from said web, a manipulating grip piece constituting a spring actuated latch pivotally connected to the inner end portion of the other section and adapted to releasably engage the inner end portion of the pin carrying section to lock said sections in interlocked pry-bar relationship, said grip piece being formed with an open end key-hole slot to receive said pivot pin to detachably connect said sections together in spring compressing plier relationship, said spring in such relationship engaging said grip piece and exerting force tending to move said sections away from each other about the axis of said pivot. 30
3. A valve tool comprising a pair of channel form sheet metal lever sections having their outer end portions formed with bifurcated jaws for use in lifting, depressing or compressing a valve spring and having their inner end portions formed to adapt them to interlock to form a rigid pry-bar type valve spring lifter and depressor, in combination with a flattened pivot pin extending between and rigidly mounted in the sides of and carried by the inner end portion of one of said sections, a latch pivotally connected to the inner end portion of the other lever section and adapted to releasably engage the inner end portion of the pin carrying section to lock said sections in interlocked pry-bar relationship, said latch being formed with an open end key-hole slot to slidably and rotatably receive said pivot pin to detachably connect said sections together in spring compressing plier relationship, and a spring adapted to exert force tending to move said sections away from each other about the axis of said pivot, and said latch being of such thickness adjacent said key-hole slot as to make a snug rotary sliding fit between the opposing inner faces of the sides of said pivot pin carrying section to maintain the sections in proper alignment in such spring compressing plier relationship. 35
4. A valve tool comprising a pair of lever sections having their outer end portions formed with bifurcated jaws for use in lifting, depressing or compressing a valve spring and having their inner end portions formed to adapt them to interlock to form a rigid pry-bar type valve spring lifter and depressor, in combination with a pivot pin carried by the inner end portion of one of said sections, a leaf spring mounted on the latter and having a free end adjacent said pin, a manipulating grip piece constituting a latch connected to the inner end portion of the other section and adapted to releasably engage the inner end portion of the pin carrying section to lock said sections in interlocked pry-bar relationship, said grip piece being formed with a key-hole slot to receive said pivot pin to detachably connect said sections together in spring compressing plier relationship, said spring in such relationship engaging said grip piece and exerting force tending to move said sections away from each other about the axis of said pivot. 40
5. A valve tool comprising a pair of lever sections having their outer end portions formed with bifurcated jaws for use in lifting, depressing or compressing a valve spring and having their inner end portions formed to adapt them to interlock to form a rigid pry-bar type valve spring lifter and depressor, in combination with a flattened pivot pin extending between and rigidly mounted in the sides of and carried by the inner end portion of one of said sections, a latch connected to the other lever section and adapted to releasably engage the pin carrying section to lock said sections in interlocked pry-bar relationship, said latch being formed with an open end key-hole slot to slidably and rotatably receive said pivot pin to detachably connect said sections together in spring compressing plier relationship. 45
6. A valve tool comprising a pair of lever sections having their outer end portions formed with bifurcated jaws for use in lifting, depressing or compressing a valve spring and having their inner end portions formed to adapt them to in- 50
7. A valve tool comprising a pair of lever sections having their outer end portions formed with bifurcated jaws for use in lifting, depressing or compressing a valve spring and having their inner end portions formed to adapt them to in- 55
8. A valve tool comprising a pair of lever sections having their outer end portions formed with bifurcated jaws for use in lifting, depressing or compressing a valve spring and having their inner end portions formed to adapt them to in- 60
9. A valve tool comprising a pair of lever sections having their outer end portions formed with bifurcated jaws for use in lifting, depressing or compressing a valve spring and having their inner end portions formed to adapt them to in- 65
10. A valve tool comprising a pair of lever sections having their outer end portions formed with bifurcated jaws for use in lifting, depressing or compressing a valve spring and having their inner end portions formed to adapt them to in- 70
11. A valve tool comprising a pair of lever sections having their outer end portions formed with bifurcated jaws for use in lifting, depressing or compressing a valve spring and having their inner end portions formed to adapt them to in- 75

terlock to form a rigid pry-bar type valve spring lifter and depressor, in combination with a pivot pin carried by the inner end portion of one of said sections, a latch connected to the other lever section and adapted to releasably engage the pin carrying section to lock said sections in interlocked pry-bar relationship, said latch being formed with a key-hole slot to receive said pivot pin to detachably connect said sections together for relative swinging movement in spring compressing plier relationship.

7. A valve tool comprising a pair of channel form sheet metal lever sections having their outer end portions formed with bifurcated jaws, in combination with a flattened pivot pin extending between and rigidly mounted in the sides of and carried by the inner end portion of one of said sections, and a leaf spring mounted on the inner face of the web of said section and having its free end adjacent said pin, the other section being formed with an open end key-hole slot to slidably and rotatably receive said pivot pin to detachably connect said sections together in spring compressing plier relationship, said leaf spring in such relationship tending to force said sections away from each other about the axis of said pivot pin.

8. A valve tool comprising a pair of lever sec-

tions having their outer end portions formed with bifurcated jaws, in combination with a pivot pin carried by the inner end portion of one of said sections, and a leaf spring mounted on the latter section and having a free end adjacent said pin, the inner end portion of the other of said sections being formed with a key-hole slot to receive said pivot pin to detachably connect said sections together in spring compressing plier relationship, said spring in such relationship exerting force tending to move said sections away from each other about the axis of said pivot.

9. A valve tool comprising a pair of lever sections having their outer end portions formed with bifurcated jaws, in combination with a pivot pin carried by the inner end portion of one of said sections, the inner end portion of the other section being formed with a socket to receive said pivot pin to detachably connect said sections together for relative swinging movement in spring compressing plier relationship, and a spring connected to one of said sections and adapted to engage a portion of the other section to exert force tending to move said sections away from each other about the axis of said pivot in such relationship.
